UNITED STATES PATENT OFFICE.

JOHN E. STRONG, OF GRAND RAPIDS, MICHIGAN.

COMBINED TABLE AND SEAT STRUCTURE.

Application filed November 18, 1926. Serial No. 148,215.

The present invention relates to combined table and seat structures; and its object is, generally, to provide an improved structure of that character which may be swung downwardly to usable position and upwardly to a compact position when not in use.

This and any other and more specific objects hereinafter appearing are attained by, and the invention finds preferable embodiment in, the structure hereinafter particularly described in the body of this specification and illustrated by the accompanying drawings, in which:

Figure 1 is an end view of the structure lowered to usable position;

Figure 2 is a view thereof in raised position;

Figure 3 is a right-hand edge view of the same in raised position;

Figure 4 is a view of the structure in raised position, the seats and their supporting members being turned outwardly; and

Figure 5 is a side view of the structure lowered to usable position.

Combined table and seat structures are frequently employed where space is limited or where it is found desirable to serve meals in kitchens, and the like. It is the object of the present invention to economize space by providing an improved structure of that character which may be lowered to usable position and raised in compact form when not in use.

In the embodiment of the invention illustrated by the accompanying drawings, a combined table and seat structure is shown comprising a support 1 secured in fixed upright position by any suitable means, as by screws 2 passing therethrough and threaded in the wall 3 of the room in which the structure is located, the bottom of this support preferably resting on the floor 4 of the room; or the support may be thus secured by screws 5 passing through its cleat 6 and threaded in the floor. A table 7 is mounted adjacent one of its ends on this support, swingably about a horizontal axis—the pintles of the hinges 8. The table top by reason of such mounting may be swung on said hinges downwardly to the usable level position seen in

Figures 1 and 5, or upwardly to the vertical position (seen in the other views) when not in use. This table top has a leg 9 mounted thereon adjacent its other or outer end swingably about a horizontal axis—the pintles of the hinges 10—so that this leg may

swing to a position in which its lower end rests on the floor to support the outer end of the table top in its level or usable position, or may swing to a position parallel with the table top in its vertical or raised position. A seat-supporting member 12 is mounted on the support 1 swingably about a vertical axis—the pintles of the hinges 13—and a second seat-supporting member 14 is mounted on the leg 9 swingably about a vertical axis—the pintles of the hinge 15—the pintles of these hinges 13 and 15 being aligned in the raised or vertical position of the table top as particularly seen in Figures 3 and 4. A seat 25 is mounted on the members 12 and 14 swingably about horizontal axes—the pintles of the hinges 26, 27 respectively. A back 16 for the seat is mounted at 17 adjacent its outer edge swingably to operative or raised position seen in Figures 1 and 5 and to a position parallel with the seat as shown in Figures 2 and 3, this back being held in usable position by suitable means as brace rods 18 pivotally mounted at 19 on the ends of the seat and having slots 20 in which the back's lugs 21 slide in raising and lowering the back.

It will be seen that the pintles of the hinges 8, 10, 26 and 27 are parallel, and that when the table top is raised and the seat is turned outwardly to the position seen in Figure 4 the table top may be lowered; but when the seat is turned inwardly to the position seen in Figures 2 and 3, the table top is thereby held in raised position.

The bottoms 23 of the members 12 and the bottoms 24 of the members 14 rest on the floor in the lowered or usable position of the structure.

As shown, the structure may comprise a pair of seats and backs, each seat having supporting members 12, 14. The pintles of the hinges 13, 15 may be withdrawn to permit detachment of either or both of the seats and their supporting members.

The invention being intended to be pointed out in the claims, is not to be limited to or by details of construction of the particular embodiment thereof illustrated by the drawings or hereinbefore described.

I claim:

1. In a structure of the character described: a support; a table top mounted adjacent one end on the support swingably about a horizontal axis to horizontal and vertical positions, and having a leg mounted ad-

5 jacent the other end of the table top swingably about a horizontal axis; a seat-supporting member mounted on said support swingably about a vertical axis; a second seat-supporting member mounted on the leg swingably about a vertical axis; a seat mounted adjacent its ends respectively on said members swingably about horizontal axes, all said horizontal axes being parallel.

10 2. In a structure of the character described: a support; a table top mounted adjacent one end on the support swingably about a horizontal axis to horizontal and vertical positions, and having a leg mounted 15 adjacent the other end of the table top swingably about a horizontal axis; a seat-supporting member mounted on said support swingably about a vertical axis; a second seat-supporting member mounted on the leg swingably about a vertical axis; a seat mounted adjacent its ends respectively on said members swingably about horizontal axes, all said horizontal axes being parallel and said vertical axes being aligned in the 20 vertical position of the table top.

25 3. In a structure of the character described; a support; a table top mounted adjacent one end on the support swingably about a horizontal axis to horizontal and vertical positions, and having a leg mounted adjacent the other end of the table top swingably about a horizontal axis; a seat-supporting member mounted on said support swingably about a vertical axis; a second seat-supporting member mounted on the leg swingably about a vertical axis; a seat mounted adjacent its ends respectively on said members swingably about horizontal axes, all said horizontal axes being parallel and the second 30 seat-supporting member resting on the floor in the horizontal position of the table top.

35 4. In a structure of the character described: a support; a table top mounted adjacent one end on the support swingably about a horizontal axis to horizontal and vertical positions, and having a leg mounted adjacent the other end of the table top swingably about a horizontal axis; a seat-supporting member mounted on said support swingably about a vertical axis; a second seat-supporting member mounted on the leg swingably about a vertical axis; a seat mounted adjacent its ends respectively on said members swingably about horizontal axes, all said horizontal axes being parallel; a back mounted 40 on the seat swingably to operative raised position and to a position parallel with the seat.

45 5. In a structure of the character described: a support; a table top mounted adjacent one end on the support swingably about a horizontal axis to horizontal and vertical positions, and having a leg mounted adjacent the other end of the table top swingably about a horizontal axis; a seat-

50 supporting member mounted on said support swingably about a vertical axis; a second seat-supporting member; a seat mounted adjacent its ends respectively on said members swingably about horizontal axes, all said horizontal axes being parallel.

55 6. In a structure of the character described: a support; a table top mounted adjacent one end on the support swingably about a horizontal axis to horizontal and vertical positions, and having a leg mounted adjacent the other end of the table top swingably about a horizontal axis; a seat-supporting member mounted on said support swingably about a vertical axis; a second seat-supporting member; a seat mounted adjacent its ends respectively on said members swingably about horizontal axes, all said horizontal axes being parallel and the second seat-supporting member resting on the floor in the horizontal position of the table top.

60 7. In a structure of the character described: a support; a table top mounted adjacent one end on the support swingably about a horizontal axis to horizontal and vertical positions, and having a leg mounted adjacent the other end of the table top swingably about a horizontal axis; a seat-supporting member mounted on said support swingably about a vertical axis; a second seat-supporting member; a seat mounted adjacent its ends respectively on said members swingably about horizontal axes, all said horizontal axes being parallel; a back mounted 65 on the seat swingably to operative raised position and to a position parallel with the seat.

70 8. In a structure of the character described, a support; a table top mounted adjacent one end on the support swingably about a horizontal axis to horizontal and vertical positions, and having a leg mounted adjacent the other end of the table top swingably about a horizontal axis; a seat supporting member attached to and extending laterally from said support; a second seat supporting member attached to and extending laterally from said leg; a seat mounted adjacent its ends respectively on said members swingably about horizontal axes, all said horizontal axes being parallel.

75 9. In a structure of the character described, a support; a table top mounted adjacent one end of the support swingably about a horizontal axis to horizontal or vertical positions, and having a leg mounted adjacent the other end of the table top swingably about a horizontal axis; a seat supporting member attached to said support and extending laterally from the lower portion thereof; a horizontal bar connected to the lower end of said leg and having a vertical portion extending upwardly from the bar spaced from said leg; a seat mounted ad-

jacent its ends respectively on said member and said vertical portion swingably about horizontal axes, all of said horizontal axes being parallel.

- 5 10. In a structure of the character described, a support; a table top mounted adjacent one end on the support swingably about a horizontal axis to horizontal and vertical positions and having a leg mounted adjacent the other end of the table top swingably about a horizontal axis; a seat supporting member mounted on said support swingably about a vertical axis; the second seat supporting member; a seat mounted adjacent one end on the first said supporting member swingably about a horizontal axis and connected adjacent its opposite end with the second seat supporting member.
- 15 11. In a structure of the character de-

scribed, a support; a table top mounted adjacent one end on the support swingably about a horizontal axis to horizontal and vertical positions and having a leg mounted adjacent the other end of the table top swingably about a horizontal axis; a seat supporting member mounted on said support swingably about a vertical axis; a second seat supporting member mounted on said leg swingably about a vertical axis; a seat mounted adjacent one end on the first said supporting member swingably about a horizontal axis and connected adjacent its other end to the upper end of the second seat supporting member.

In testimony whereof I have hereunto set my hand at Grand Rapids, Michigan, this 10th day of November, 1926.

JOHN E. STRONG.
